A. J. WHITFIELD,
WRENCH.
APPLICATION FILED APR. 23, 1917.

Patented Mar. 5, 1918.

UNITED STATES PATENT OFFICE.

ARTHUR JAMES WHITFIELD, OF BOSTON, MASSACHUSETTS, ASSIGNOR TO TRIMONT MANUFACTURING COMPANY, OF BOSTON, MASSACHUSETTS, A CORPORATION OF MAINE.

WRENCH.

1,258,628.

Specification of Letters Patent.

Patented Mar. 5, 1918.

Application filed April 23, 1917. Serial No. 163,816.

To all whom it may concern:

Be it known that I, ARTHUR JAMES WHITFIELD, a citizen of the United States, and resident of Boston, in the county of Suffolk and State of Massachusetts, have invented an Improvement in Wrenches, of which the following description, in connection with the accompanying drawings, is a specification, like letters on the drawings representing like parts.

My present invention relates to wrenches such as shown in my prior Patent No. 1,187,690, issued June 20, 1916, and my object is to improve, strengthen and perfect the type of wrench therein illustrated and to simplify the process of manufacturing same.

In making wrenches of the type mentioned, especially in the larger sizes of such wrenches, where great strains are brought upon the wrench parts, and particularly where the swinging frame carrying the movable jaw member is of steel, as explained in my said prior patent, a difficulty has been found in that the wings of the steel frame were apt to "spring" and also to crush down and consequently impair the bearing shoulders against which the wings rested during use. As the wings of the swinging frame must necessarily have considerable play in order to be free to have the movable jaw part automatically seat upon the work, and grip the same in the manner of a "Stillson" wrench, it has been extremely difficult to devise means which would strengthen and correct this difficulty and still provide for the freedom of movement required. My invention is directed to correcting this difficulty, and furthermore to provide a simple, efficient, inexpensive and very powerful strengthening construction.

Other features of the invention, combination of parts and novel details will be hereinafter more fully pointed out and claimed.

Referring to the drawings, illustrating a preferred embodiment of my invention,

Figure 1 is a side view of my improved wrench;

Fig. 2 is a front view; and

Fig. 3 is a fragmentary view; and

Fig. 4 is a detail of one of the reinforcing parts.

Referring to the drawings, 1 indicates the usual handle portion of the wrench carrying a fixed jaw 2 at the upper end which, preferably, is removable and held in position on

the handle 1 by dovetailed connection consisting in a depending central part 3 fitting in a recess 4 at the upper end of the wrench and held by a rivet 5. The movable jaw member 6 is formed with a portion 7 to co-operate with the jaw 2 and with a lower portion 8 threaded to receive the adjusting nut 9 and to extend through the swinging frame 10, which frame is pivoted at 11, to the handle 1. This frame is of usual construction and preferably an all steel frame as shown in my said prior patent. The wings 12 and 13, of said frame extend forwardly at either side of the upper part of the handle 1 and are in position to rest upon a pair of lugs 14 and 15 respectively, which lugs extend backwardly as shown at 16, Figs. 1 and 3, to constitute a pair of guides for the lower part 8 of the jaw member 6. Between these lugs and extending into the adjacent part of the handle 1 is a recess 17 as indicated in dotted lines, Figs. 1 and 3, to receive a grooved head 18 of a plunger 19 around which plunger is a spring 20, normally forcing the head 18 outwardly and consequently bearing against the jaw member 6 and normally forcing it and the frame 10 on the pivot 11 until the wings 12 and 13 are resting on the lugs 14 and 15. This construction necessitating a recess with in this part of the wrench, was an element of weakness in the lugs 16, as formerly made, and my present invention contemplates the strengthening of these lugs as one of the improved features in the present construction. In prior constructions these lugs were only of sufficient extent to provide a shoulder for the bearing wing portions 12 and 13 thereon and this resulted, because of the necessity of the construction, freedom of movement of the wrench parts, and unbraced wings, in breaking down, crushing and wearing or leveling of the small shoulders and consequently the forcing apart of the wings 12 and 13, thus impairing the efficiency of the wrench. Accordingly I form the lugs 14 and 15 of substantially doubled thickness and also slightly bevel the contacting faces 21 and 22 as illustrated in Fig. 2, similarly beveling the corresponding contacting surfaces of the wings 12 and 13 if desired, so that a normal pressure on the lugs will force the free ends of said wings together rather than to spread them apart. In the thicker portion of these lugs 14 and 15

- 15 I provide a recess as indicated at 23, Fig. 3, which recess is preferably circular in form and of sufficient diameter and size to receive a round steel disk 24, which extends upwardly a sufficient extent to overlap the wings 12 and 13 as indicated at 25, Fig. 1, this disk being preferably welded directly onto the lugs and the recess provided therefor.
- 10 As thus constructed, my improved wrench provides an economical construction which prevents the steel frame 10 from breaking down the lugs during use, which provides a guide for same frames and a reinforcing 15 and strengthening for the lugs and yet permits full freedom of movement of the frame and jaw member of the wrench. The welding construction, furthermore, using strong steel disks as guides, and also strengthening 20 the lugs to which said disks are welded, is an advantage of my present invention. Consequently my improved wrench obviates the difficulties and weakness formerly experienced and prevents the steel frame 10 from 25 crushing or wearing the lugs on the handle portion, which latter may be and usually are of softer metal, for economy, and guides and strengthens the wings of the frame, effectively preventing them from springing 30 apart, while still permitting freedom of movement, in all directions and seating of the jaw member on the work. Furthermore, the process above described of recessing the lug members 14 and 15, which are forged 35 integrally with the handle 1, with the recesses 23 therein, and then applying the metal disks 24, preferably of steel, in said recesses and welding the same, enables a steel strengthening and bearing member to 40 be readily, easily, quickly and economically applied by a simple electrical welding, thus reinforcing both the lugs and the steel wings of the frame by a steel bearing member, which will be most efficient in service.
- 45 The steel disks may be punchings from a plate of proper thickness and therefore are very inexpensive.
- My invention is further described and defined in the form of claims as follows:
- 50 1. A wrench of the kind described, having a jaw portion, and a pivoted guide frame, a movable jaw member adjustably carried by said guide frame, wings on the frame extending at each side of the jaw portion of the wrench, lugs on said jaw portion upon which the wings of said frame rest, and a steel disk welded to said lugs and overlapping the said wings permitting freedom of movement of the frame and jaw member 55 while holding said wings in normal position.
2. A wrench of the kind described, having a jaw portion, and a pivoted guide frame, a movable jaw member adjustably carried by said guide frame, wings on the frame extending at each side of the jaw portion of
- the wrench, lugs on said jaw portion, the bearing faces of said lugs for said wings being inwardly beveled.
3. A wrench of the kind described, having a jaw portion, and a pivoted guide frame, a movable jaw member adjustably carried by said guide frame, wings on the frame extending at each side of the jaw portion of the wrench, lugs on said jaw portion, the bearing faces of said lugs for said wings being inwardly beveled, and guide members carried by said lugs and overlapping the wings at all times during the tilting movement of the frame.
4. A wrench of the kind described, having a jaw portion, and a pivoted guide frame, a movable jaw member adjustably carried by said guide frame, wings on the frame extending at each side of the jaw portion of the wrench, lugs on said jaw portion, recesses in said lugs adapted to receive a steel disk secured therein, said disks being of sufficient diameter to overlap the adjacent wing portions of the frame.
5. The process of manufacturing the fixed jaw portion of a wrench of the kind described, said wrench being adapted to receive a tilting frame carrying an adjustable jaw member, which consists in forming the fixed jaw portion with lugs on each side of greater thickness than the metal of said tilting frame, beveling the frame contacting surfaces of said lugs inwardly, recessing the outer surfaces of said lugs and then applying to said recesses metal disks adapted to fill said recesses and to overlap the tilting frame and welding said disks thereto.
6. A wrench including a stock, a fixed jaw carried by the stock, a yoke pivoted upon the stock, a movable jaw carried by the yoke to coöperate with the fixed jaw, and inwardly sloping interengaging means carried by the yoke and stock respectively for urging the sides of the yoke toward the stock co-incident with the outward pivotal movement of the yoke under leverage tension thereon.
7. A wrench including a stock, a fixed jaw carried by the stock, a yoke pivoted upon the stock, a movable jaw carried by the yoke to coöperate with the fixed jaw, inwardly sloping shoulders carried by the yoke, and inwardly sloping shoulders carried by the stock and engaging the shoulders of the yoke for urging the sides of the yoke toward the stock co-incident with the outward pivotal movement of the yoke under leverage tension thereon.
8. A wrench including a stock, a fixed jaw carried thereby, a yoke pivoted upon the stock and provided with guide wings embracing the stock, a movable jaw carried by the yoke to coöperate with the fixed jaw, inwardly beveled shoulders formed on the free extremities of said wings, and inwardly beveled shoulders formed on the

beveled shoulders formed on the stock and engaging the shoulders of said wings for urging the wings toward the stock co-incident with the outward pivotal movement of the yoke under leverage tension thereon.

9. A wrench including a stock, a fixed jaw carried thereby a yoke pivoted at one extremity upon the stock and provided at its opposite extremity with guide wings 10 fronting opposite sides of the stock, inwardly beveled shoulders formed on the free rear edges of said wings, a movable jaw carried by said yoke to coöperate with the fixed jaw, outstanding posts formed on opposite sides of the stock and freely receiving the inner extremity of the said movable jaw, and inwardly beveled shoulders formed

on the forward edges of said posts to co-act with the beveled shoulders of the said wings with the shoulders of the wings movable to gradually seat throughout their length beneath the shoulders of the post for urging the wings toward the stock co-incident with the outward pivotal movement of the yoke upon the stock under leverage tension upon the said yoke.

In testimony whereof, I have signed my name to this specification, in the presence of two subscribing witnesses.

ARTHUR JAMES WHITFIELD.
